UNITED STATES PATENT OFFICE.

JOSEPH A. WILLIAMS, OF CLEVELAND, OHIO, ASSIGNOR TO THE K. W. IGNITION COMPANY, OF CLEVELAND, OHIO, A CORPORATION OF OHIO.

INTERNAL-COMBUSTION ENGINE.

1,098,539.

Specification of Letters Patent.

Patented June 2, 1914.

Application filed December 19, 1910. Serial No. 598,038.

To all whom it may concern:

Be it known that I, JOSEPH A. WILLIAMS, a citizen of the United States, residing at Cleveland, in the county of Cuyahoga and State of Ohio, have invented a certain new and useful Improvement in Internal-Combustion Engines, of which the following is a full, clear, and exact description.

This invention relates to internal combustion engines and particularly to two-cycle engines.

It is a well known fact that a two-cycle engine is an admirable prime mover and in some respects is superior to a four-cycle engine, but has the disadvantage that as compared with a four-cycle engine it has a small range in speed. It is also well known that when the speed of a two-cycle engine is decreased by closing down the throttle valve or by "throttling down" the engine, it is necessary in order that an explosive charge may be drawn into the cylinder that the needle valve be opened and that the mixture be made very rich by an excessive flow of gasoline, and even though the mixture is made as rich as possible, the engine is very unreliable and uncertain in its action, the explosions or ignitions taking place with more or less irregularity and the engine often "back-fires." Furthermore, after the engine has operated for a period at a low speed in the unsatisfactory manner above stated, and after the speed has been increased by opening the throttle valve, the operation of the engine is still unsatisfactory for a considerable time due to the fact that more or less gasoline was condensed in the crank case and ports and passageways leading to the cylinder, with the result that the explosions or "hitting" is not regular, until this condensed gasoline has been carried away.

The present invention has for its main object to provide means whereby a two-cycle engine can be made more flexible in its speed range and can be made nearly as efficient at low speed as a four-cycle engine.

I accomplish the above object by providing means whereby when the engine is throttled, it is caused to hit regularly but at a less number of times in a given number of compression strokes than normally or when it is operating at a higher speed and

with the throttle valve open. In this case when the engine is throttled down, I provide means for causing each cylinder to hit or to have a charge ignited therein at each alternate compression stroke instead of at each compression stroke, and I thereby convert the engine from a two-cycle to a four-cycle engine as far as the ignition or rate of ignitions is concerned.

The above is accomplished in the embodiment of my invention here shown by causing the ignition system to be rendered inoperative or inactive at certain regularly occurring compression strokes when the engine is throttled, although an igniting arc is produced in the cylinder at each compression stroke when the engine is operating at normal or above a predetermined speed. Preferably, the ignition system is controlled automatically by the operation of the throttle lever, which in an automobile, for instance, for which my invention is particularly adapted, is carried by the steering wheel.

My invention may be further briefly summarized as consisting in certain novel combinations and arrangements of parts which will be described in the specification and set forth in the appended claims.

For a better understanding of my invention, reference is had to the accompanying drawing which is a diagrammatic representation of a two-cycle engine and one embodiment of my invention which is applied thereto.

Referring now to the drawing, 10 represents a two-cycle engine which for convenience of description and illustration is shown as provided with three cylinders A, B and C, although it is to be understood that my invention may be employed with or applied to a two-cycle engine having any number of cylinders. The cylinders are provided respectively with pistons 11 which are connected in the usual manner to the cranks of a crank shaft 12.

I employ in connection with the engine 100 an ignition system which normally produces in each cylinder at each compression stroke an igniting arc or spark, the ignition system in this case including a high tension magneto having a low tension winding 13 105 and a high tension winding 14, the former

having in its circuit a make-and-break device or circuit breaker 15 which may be of any construction, and the high tension winding being connected by a conductor 16 to the movable arm 17^a of a distributor 17 having in this case three stationary contacts or segments 17^b which are connected by conductors 18 to spark plugs 19, one provided for each cylinder. Of course both the circuit breaker cam and distributor arm are each driven or operated by the engine at a fixed speed relative to the engine, or at a constant speed ratio, whether ignition takes place in a cylinder at each compression stroke, or is restricted to one of a number of compression strokes in a manner hereinafter explained. The ignition system also includes a grounding switch 20 in the circuit of the primary or low tension winding 14, this switch 20 being for the purpose of manually rendering inoperative or throwing out of operation the ignition system by short-circuiting the primary. The ignition system so far described is old and well known, and I claim no novelty therein as far as the ignition system alone is concerned.

It will be understood that when the circuit breaker 15, distributor 17, and magneto armature are operated at the proper or usual rates of speed for a two-cycle engine, an igniting arc will be produced in each cylinder at each compression stroke of the piston therein, the distributor being driven at full speed or at crank-shaft speed.

While I am aware that my invention in its broad aspect may be carried out by other specific forms of apparatus than the one here shown, I shall describe my invention only in its preferred embodiment.

To render the ignition system inactive during certain compression strokes when the engine is throttled down for the reasons previously stated, I employ a device 21 which is somewhat similar to the distributor 17, but is, in fact, a grounding switch, including a rotating arm 21^a which will be driven by the engine and three spaced contacts or segments 21^b, and this switch arm 21^a, for a purpose to be explained, is operated at one-half the speed of the arm 17^a of the distributor or at one-half crank-shaft speed; whereas the distributor arm is operated at full or crank-shaft speed. The switch arm 21^a is grounded, the arm being grounded by a conductor 22, as shown in the drawing, and the three contacts or segments 21^b are all connected to a common conductor 23. This conductor 23 is adapted to be connected to the low tension or primary winding 13 of the magneto by a conductor 24, and by a switch 25 including two insulated contacts 25^a and 25^b, and a contact 25^c which is adapted to bridge the contacts 25^a and 25^b and is carried by the throttle lever 26, which

is arranged in the usual manner with respect to the steering post and the steering wheel 27, forming part of the usual steering mechanism of a motor vehicle.

It will be seen that when the throttle valve is in normal position and until the engine has been throttled down a predetermined amount by moving the throttle lever 26, the ignition system is disconnected from the switch 21, but when the engine is throttled down to an extent such that the bridging contact 25^c of the switch 25 bridges the contacts 25^a and 25^b, the primary or low tension winding 13 is grounded at both terminals and short circuited independently of the circuit breaker 15, when the switch arm 21^a is in engagement with any one of the segments 21^b, but when the switch arm is between two segments, then the switch 21 does not short circuit the winding. Consequently, if the switch 25 is closed when the switch arm and distributor arm are in the positions shown or when they each engage a contact, then there will be no arc formed at the spark plug which is connected to the segment engaged by the distributor arm or in this case at the spark plug in cylinder A. But as the switch arm 21^a is rotated at one half the speed of the distributor arm, when the latter reaches the next segment, or reaches the segment connected to the spark plug, in cylinder B, the switch arm 21 will be between two of the segments 21^b and consequently, an arc will be formed in the cylinder B in the usual manner, the low tension winding being in this particular instance not grounded by the switch 21. When the distributor arm reaches the third segment or the segment connected to the plug in cylinder C, the switch arm 21^a will again be on a segment, and consequently in cylinder C, at this time no arc will be formed and no ignition of the explosive mixture will take place. When the distributor arm again reaches the contact connected to the plug in cylinder A, the switch arm 21^a will now be between two segments, and at this compression stroke of the piston in cylinder A, an arc will be formed, and ignition will take place in the usual manner, whereas at the previous compression stroke in this cylinder no ignition took place. In a similar manner at the next compression stroke of the piston in cylinder B, which had previously hit, there will be no arc and no ignition, and at the next compression stroke of the piston in cylinder C, which had previously missed, there will be an arc and ignition. Therefore the engine acts as regards the number of ignitions in a series of strokes exactly as a four-cycle engine, each cylinder hitting at each alternate compression stroke of the piston in that cylinder, and missing on the other compression strokes. Of course, when the switch 25 is opened by moving the

throttle lever 26 so as to open the throttle, the engine is automatically reconverted to a two-cycle engine, and the switch 21 becomes inoperative, although the arm 21^a is continuously rotated by the engine.

By converting the engine from a two-cycle to a four-cycle engine, it will not be necessary on throttling down the engine to open the needle valve to obtain an excess of gasoline, and instead of igniting a single small charge of an exceedingly rich mixture, I supply to the cylinder during the two strokes of the piston, two charges of a leaner mixture, and in this manner I obtain a charge which is more satisfactory and more effective and reliable for ignition than a smaller charge richer with gasoline. While it is true that on the completion of the downward stroke of the piston a part of the charge which had been previously admitted to the cylinder and compressed during the inactive compression stroke, is lost, nevertheless enough of the charge remains in the cylinder to form with the next charge admitted, a charge which is much more effective and more reliable than the charge in a cylinder of an ordinary two-cycle engine when throttled down to obtain a slow speed.

Having thus described my invention, what I claim is:

1. In combination with a two-cycle internal combustion engine, an ignition system for causing ignition in a cylinder of the engine at each compression stroke comprising a member adapted to be driven by the engine at a constant speed ratio, and means for restricting the ignition to one of a number of compression strokes without altering the speed ratio of said member and of the engine.

2. In combination with a two-cycle internal combustion engine, an ignition system for causing ignition in a cylinder normally at each compression stroke comprising a member adapted to be driven by the engine at a constant speed ratio, and means for preventing ignition in the cylinder at each alternate compression stroke without altering the speed ratio of said member and of the engine.

3. A two-cycle internal combustion engine having means for causing an igniting arc in a cylinder at each compression stroke of the piston, or at each alternate compression

stroke, said means comprising an ignition system and a switch for rendering the system inoperative at each alternate compression stroke.

4. A two-cycle internal combustion engine having ignition apparatus for causing ignition in a cylinder normally at each compression stroke of the piston, or at each alternate compression stroke when the engine is throttled a predetermined amount.

5. A two-cycle internal combustion engine having ignition apparatus for causing an igniting arc in a cylinder at each compression stroke of the piston when the engine is operating at normal speed, or at each alternate compression stroke when the speed is decreased by throttling the engine.

6. A two-cycle internal combustion engine having an ignition system for causing ignition in a cylinder at each compression stroke of the piston, and means for changing the number of ignitions in a series of compression strokes as the engine is throttled.

7. In combination with a two-cycle engine, an ignition system for normally causing an igniting arc in a cylinder at each compression stroke of a piston, and means for preventing the formation of an igniting arc at alternate compression strokes.

8. In combination with a two-cycle engine, an ignition system for normally causing an igniting arc in a cylinder at each compression stroke, and means for preventing the formation of an arc at alternate compression strokes when the engine is throttled, comprising a switch which periodically renders the ignition system inactive.

9. In combination with a two-cycle engine, an ignition system for normally causing an igniting arc in a cylinder at each compression stroke, and means for preventing the formation of an arc at each alternate compression stroke when the engine is throttled comprising a rotating grounding switch connected to the ignition system and adapted to periodically render the system inoperative.

In testimony whereof, I hereunto affix my signature in the presence of two witnesses.
